UNITED STATES PATENT OFFICE

105,658

DESIGN FOR A DRESS

Rose Feintuck, New York, N. Y.

Application July 14, 1937, Serial No. 70,404

Term of patent 3½ years

To all whom it may concern:

Be it known that I, Rose Feintuck, a citizen of the United States of America, residing in Manhattan, county of New York, and State of New York, have invented a new, original, and ornamental Design for a Dress, of which the following is a specification, reference being had to the accompanying drawing, forming part thereof, wherein,

The circular elements on the front waist portion of the dress represent rose buds.

I claim:

The ornamental design for a dress, substantially as shown and described.

ROSE FEINTUCK.
